(57) **CLAIM**

The ornamental design for a stop for a trigger button of a video game controller, as shown and described.

DESCRIPTION

FIG. 1 is a bottom perspective view of a stop for a trigger button of a video game controller, showing the new design.

FIG. 2 is a top perspective view thereof.

FIG. 3 is a front perspective view thereof.

FIG. 4 is rear perspective view thereof.

FIG. 5 is a right-side perspective view thereof.

FIG. 6 is a left-side perspective view thereof.

FIG. 7 is a bottom, front, right-side perspective view thereof.

FIG. 8 is a top, front, left-side perspective view thereof.

FIG. 9 is a bottom perspective view of the stop for a trigger button of a video game controller, showing a variant of the new design.

FIG. 10 is a top perspective view of the variant of FIG. 9.

FIG. 11 is a front perspective view of the variant of FIG. 9.

FIG. 12 is rear perspective view of the variant of FIG. 9.

FIG. 13 is a right-side perspective view of the variant of FIG. 9.

FIG. 14 is a left-side perspective view of the variant of FIG. 9.

FIG. 15 is a bottom, front, right-side perspective view of the variant of FIG. 9; and,

FIG. 16 is a top, front, left-side perspective view of the variant of FIG. 9.

In FIGS. 1 and 9, the environment of the video game controller and an associated adapter are shown in broken lines for illustrative purposes only, and form no part of the claimed design.

1 Claim, 8 Drawing Sheets
